Duraflam Flex Neck Utility Lighter. By Duraflame. Dated Jan. 11, 2018. Found online [Feb. 23, 2021]. <https://www.duraflame.com/products/lighters-matches/duraflame-flex-neck-utility-lighter> (Year: 2018).*

Primary Examiner — Marissa J Cash*Assistant Examiner* — William B Melliar(74) *Attorney, Agent, or Firm* — The H.T. Than Law Group(57) **CLAIM**

We claim the ornamental design for a lighter, as shown and described.

DESCRIPTION

FIG. 1 is a perspective view of an ornamental design for a lighter according to the present invention;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The broken lines illustrate portions of the design for a lighter and form no part of the claimed design.
